UNITED STATES PATENT OFFICE.

JAMES H. CRAMPHORN, OF MEDFORD, MASSACHUSETTS, ASSIGNOR TO CHARLES SUMNER KNOWLES, OF NEW BEDFORD, AND JOHN HENRY PARKER, OF CLIFTONDALE, MASSACHUSETTS.

ROSETTE FOR ELECTRIC WIRING.

SPECIFICATION forming part of Letters Patent No. 886,448, dated November 12, 1901.

Application filed June 14, 1901. Serial No. 64,515. (No model.)

To all whom it may concern:

Be it known that I, JAMES H. CRAMPHORN, of Medford, in the county of Middlesex and State of Massachusetts, have invented a new 5 and useful Rosette for Electric Wiring, of which the following is a specification, reference being had to the accompanying drawings, in which—

Figure 1 is a plan of my rosette. Fig. 2 is 10 an elevation. Fig. 3 is a section on line 3 3 of Figs. 2 and 5. Fig. 4 is a section on line 4 4 of Fig. 1, and Fig. 5 is a section on line 5 5 of Fig. 1 with the lamp-cords omitted.

The object of my invention is to prevent 15 short-circuiting at the rosette, which heretofore has happened because the bare ends of the lamp-cords and their binding-posts have been in a chamber which could not be practically protected from the entrance of dust 20 and lint, the result being that the accumulation of dust and lint in that chamber bridged the space between the two binding-posts and in time formed a conductor which short-circuited the lamp.

In my rosette the binding-posts are so separated by the material of the rosette that it 25 is impossible for any dust, lint, or other foreign matter to collect between them, and this is the distinguishing peculiarity of my invention.

In the drawings I have shown the best form 30 in which I have contemplated applying my new principle, the substance of the matter being that the binding-posts A A' are on opposite sides of base B and are separated by the boss B', which is perforated at b to receive the cords D, the two ends of the cords extending, respectively, to the two binding-posts A A'. The cord-hole b in the boss opens into a 35 recess b', which allows the knot d to be formed to make a secure connection between the cords

D and the rosette, and the ends d' of the knot d are protected by the sides of the boss, these ends d' being passed, respectively, through holes b², leading from recess b' to the recesses 45 b³ in boss B', which recesses b³ receive the binding-posts A A'. The binding-posts A² A³ are for the feeder-wires.

The cords D are first passed through the hole b and out through the recess b'. The 50 two ends of cords D are then knotted together. One end of the knot is passed through one hole b² to the binding-post A and the other end of the knot through the other hole b² to the binding-post A' and the bare wires secured to the binding-posts A A' in the usual 55 way. One important function of the holes b² is to serve as guides, greatly facilitating the attachment of the cords to the rosette. These holes b² also effectually prevent dust and lint 60 or other foreign matter from forming a bridge between the binding-posts A A'.

What I claim as my invention is—

1. The rosette above described made up of a base and a boss on that base separating the 65 binding-posts of the lamp-cords, which boss has a central hole for the two lamp-cords, a side recess for the knot connecting the ends of the two lamp-cords, and two side holes through which the ends of the knot in the 70 lamp-cords extend to the binding-posts.

2. In a rosette of the kind above described a base and a boss made integral with a central cord-hole in the boss, a side recess in the boss into which the central cord-hole opens, 75 two side holes opening out of the side recess, and two other side recesses into which the side holes open respectively.

JAMES H. CRAMPHORN.
